United States Patent Office

Des. 185,218

Patented May 19, 1959

185,218

RAILING

John W. Linley, Jr., Anderson, S.C., assignor of fifty percent to David P. Watkins, Anderson, S.C.

Application March 9, 1956, Serial No. 40,520

Term of patent 14 years

(Cl. D13—7)

Fig. 1 is a perspective view of a railing showing my new design; and

Fig. 2 is a sectional view taken along the line 2—2 in Fig. 1.

The side of the railing not shown in the drawing is substantially like the side shown.

I claim:

The ornamental design for a railing, as shown and described.
